UNITED STATES PATENT OFFICE

2,545,758

STACKING RECEPTACLE

Wilson F. Best, Grand Rapids, Mich.

Application November 9, 1945, Serial No. 627,669

17 Claims. (Cl. 220—97)

1

This invention relates to improvements in stacking receptacles.

The main objects of this invention are:

First, to provide a receptacle of the stacking box type which is relatively light in weight and at the same time capable of withstanding severe usage and is very durable.

Second, to provide a receptacle of this type which is adapted to sustain heavy loads when a series of loaded receptacles are stacked one upon another and one which may be dragged on a floor or platform without injury thereto.

Third, to provide a receptacle of this type which has a wide variety of uses such as in the handling of various materials in stores and factories and one in which the portions most exposed to wear are reinforced and protected whereby wear is minimized.

Objects relating to details and economies of the invention will appear from the description to follow. The invention is defined and pointed out in the claims.

Preferred embodiments of the invention are illustrated in the accompanying drawings, in which:

Fig. 1 is a side elevation of a receptacle of the stacking box type embodying my invention.

Fig. 2 is an enlarged fragmentary view in transverse section on a line corresponding to line 2—2 of Figs. 1 and 3.

Fig. 3 is an enlarged fragmentary inverted view with the stacking iron or bail in erected position.

Fig. 4 is an enlarged fragmentary view in section on a line corresponding to line 4—4 of Fig. 3 of a pair of the receptacles in stacked relation.

Fig. 5 is an enlarged fragmentary view partially in longitudinal section on a line corresponding to line 5—5 of Fig. 3.

Fig. 6 is a perspective view of one of the outer or side bottom bar socket members.

Fig. 7 is a perspective view of one of the intermediate bottom bar socket members.

Fig. 8 is an end perspective view of a modified form or embodiment of my invention in which the bottom, side and end walls are removably associated with the elements constituting the frame parts.

Fig. 9 is an enlarged fragmentary view in section on line 9—9 of Fig. 8.

In the embodiment of my invention shown in Figs. 1 to 7 inclusive, the walls are permanently secured to associated parts. In the embodiment of my invention shown in Figs. 8 and 9 the walls are removably associated with the parts consti-

2

tuting the frame to permit removal or replacement thereof. In the preferred embodiment the walls are formed of fiberboard while in the modified form or embodiment they may be made of less durable stock, one of the objects being to permit removal thereof in the event of the walls becoming soiled.

In the embodiment of my invention illustrated in Figs. 1 to 6 inclusive, the bottom 1, side walls 10 2, and end walls 3 are formed of fiberboard or hard fiber stock, the bottom and side walls being preferably formed integrally. The uprights 4 are of angled section disposed with the angles facing inwardly, the ends of the bottom and side walls 15 being disposed within the uprights and secured thereto as by the rivets 5.

The bottom end cross pieces 6 are of angle section and disposed facing inwardly, being fixedly secured to the corner uprights as by welding indicated at 1, see Fig. 8.

The lower ends of the end walls are disposed with these bottom cross pieces and fixedly secured thereto as by the rivets 8. The top, side and end pieces or rails 9 and 10 are disposed on the outer 25 sides of the side and end walls and secured thereto as by rivets 11.

Angled corner irons 12 are secured to the side and end rim members as indicated at 13 and are provided with pintle receiving sockets 14 for the 30 pintles 15 for the stacking bails or irons 16.

The side rim members 10 are provided with downwardly facing reinforcing irons 17 of U-section embracing intermediate portions of the side rim pieces and the upper edges of the side walls and fixedly secured as by means of the rivets 17. These reinforcing irons prevent outward springing of the sides of the box and constitute wear irons, being positioned to support the stacking bails when in erected position, see Fig. 4, and protecting the edges when objects are slid across the top of the walls. The ends of the receptacle are provided with similar reinforcing irons 18.

Outer and intermediate bottom bars 19 and 20 45 are provided, these bars supporting and protecting the bottom and also serving as skid bars. The bars are secured to the bottom intermediate their ends as by the rivets 21. The ends of the bars are supported and protected by the upwardly facing 50 channel-shaped outer and intermediate socket members 22 and 23.

The intermediate socket members 23 are provided with flanges 24 at their side edges which are secured to the bottom by the rivets 25, the 55 flanges having tongues 26 which are disposed

above the bottom end cross pieces. The ends of the bottom bars are disposed between the sockets and the end cross pieces, as shown in Fig. 5.

The outer socket members 22 have inner flanges 27 which are riveted to the bottom at 28, these flanges having tongues 29 corresponding to the tongues 28 and projecting above the bottom end cross pieces.

The outer flanges 30 of the outer socket members are turned upwardly in lapping relation to the side walls and secured thereto as by the rivets 31. These flanges have tongues 32 which project within the corner uprights.

The outer socket members are of such length that they serve as wear plates engaging the 15 stacking bails as shown in Fig. 4. The flanges projecting up at the sides of the side walls prevent wearing or abrading of the side walls and their engagement with the offsets 33 of the stacking bails—see Fig. 4.

The embodiment of my invention shown in Figs. 8 and 9 is substantially as described except that the lower ends of the uprights and the end cross members are connected by inwardly facing angled bottom side pieces 34, these being secured to the corner uprights by rivets or spot welding as indicated at 35. In this embodiment, the tongues of the socket members are spot welded to the end bottom cross pieces as indicated at 36. That may desirably be done in the preferred embodiment although very satisfactory results may be had without doing that.

This arrangement of parts results in a receptacle which may be made of relatively light material and at the same time is capable of withstanding very severe usage and wear. The bottom is effectively supported and protected by the bottom bars which constitute skids or runners when the receptacle is dragged along a floor or platform or the bed of trucks or the like.

The receptacles are used in a wide variety of relations as in factories, for the handling of merchandise in wholesale and retail establishments, for deliveries and various other uses. Where it is desired to renew the walls, they are not attached to the other parts of the frame but may be removed and replaced, the upper edges of the side and end walls being engaged under the reinforcing irons. As a removable wall structure, my present invention is in some respects an embodiment and improvement upon the structure shown in my Patent 2,297,097, dated September 29, 1942. However, the embodiment shown in Figs. 1 to 7 inclusive in which the walls are permanently built into the structure is highly desirable and has a 55 wide variety of uses.

I have not attempted to illustrate or describe other embodiments or adaptations as it is believed that this disclosure will enable those skilled in the art to embody or adapt my invention as may be desired.

Having thus described my invention, what I claim as new and desire to secure by Letters Patent is:

1. In a receptacle having bottom, side and end walls reinforcing and stacking structure comprising, inwardly facing angled corner uprights, inwardly facing angled bottom cross pieces secured to the bottoms of the corner uprights, the ends of the side and end walls being arranged within the corner uprights, the ends of the bottom and the lower ends of the end walls being disposed within the bottom cross pieces, side and end rim pieces secured on the outer sides of the side and end walls at the top thereof and in overlapping

relation to the corner uprights, angled corner brackets secured to the said side and end rim pieces and constituting reinforcing elements, said corner brackets being provided with pintle openings extending along the end walls and at the top of said brackets, downwardly facing reinforcing irons of U-section embracing intermediate portions of the side and end rim pieces and the upper edges of the side and end walls and fixedly secured thereto, stacking bails provided with inturned pintles engaging the pintle openings of said corner brackets and swingable to erected position with the cross members thereof supported on the side reinforcing irons, longitudinally disposed side and intermediate bottom bars disposed below and secured to the bottom and constituting slide bars, and outer and intermediate sockets receiving the ends of the bottom bars and having attaching flanges, the attaching 10 flanges of the intermediate socket members being secured to the bottom and being provided with tongues disposed within the bottom flanges of the bottom cross pieces, the outer socket members being provided with inner attaching flanges 15 secured to the bottom and having tongues disposed within the bottom flanges of the bottom cross pieces, and angularly disposed outer flanges lapped upon and secured to the side walls and having tongues engaged within the side flanges 20 of the corner upright, the outer socket members being of such length as to constitute stacking bail wear members.

2. In a receptacle having bottom, side and end walls, reinforcing and stacking structure comprising inwardly facing angled corner uprights, inwardly facing angled bottom cross pieces secured to the bottoms of the corner uprights, the ends of the side and end walls being arranged within the corner uprights, the ends of the bottom and the lower ends of the end walls being disposed within the bottom cross pieces, side and end rim pieces secured on the outer sides of the side and end walls, angled corner brackets secured to the said side and end rim pieces and constituting reinforcing elements, said corner brackets being provided with pintle openings extending along the end walls and at the top of said brackets, stacking bails provided with inturned pintles engaging the pintle openings of said corner brackets, longitudinally disposed side and intermediate bottom bars disposed below the bottom and constituting slide rails, and outer and intermediate sockets receiving the ends of the bottom bars and having attaching flanges, the attaching 30 flanges of the intermediate socket members being secured to the bottom and being provided with tongues disposed within the bottom flanges of the bottom cross pieces, the outer socket members being provided with inner attaching flanges secured to the bottom and having tongues disposed within the bottom flanges of the bottom cross pieces, and angularly disposed outer flanges lapped upon and secured to the side walls and having tongues engaged within the side flanges 35 of the corner uprights.

3. In a receptacle having bottom, side and end walls, reinforcing and stacking structure comprising inwardly facing angled corner uprights embracing the ends of the side and end walls, inwardly facing angled bottom cross pieces secured to the lower ends of the corner uprights, the ends of the bottom and the lower ends of the end walls being disposed within the bottom cross pieces, side and end rim pieces secured on the outer sides of the side and end walls at the top thereof and in overlapping

top thereof and in overlapping relation to the corner uprights, angled corner brackets secured to the said side and end rim pieces and constituting reinforcing elements, said corner brackets being provided with pintle openings extending along the end walls and at the top of said brackets, downwardly facing U-shaped reinforcing members embracing intermediate portions of the side rim pieces and fixedly secured thereto, stacking bails provided with inturned pintles engaging the pintle openings of said corner brackets and swingable to erected position with the cross members thereof supported on the side reinforcing members, longitudinally disposed side and intermediate bottom bars disposed below the bottom and constituting slide rails, and sockets receiving the ends of the bottom bars and constituting wear members, said sockets having attaching flanges provided with tongues engaged within the bottom cross pieces, the outer socket members having parts overlapping the side walls and being of such length as to constitute stacking bail wear members.

4. In a receptacle having bottom, side and end walls, reinforcing and stacking structure comprising inwardly facing angled corner uprights embracing the ends of the side and end walls, inwardly facing angled bottom cross pieces secured to the lower ends of the corner uprights, the ends of the bottom and the lower ends of the end walls being disposed within the bottom cross pieces, side and end rim pieces secured on the outer sides of the side and end walls at the top thereof and in overlapping relation to the corner uprights, angled corner brackets secured to the said side and end rim pieces and constituting reinforcing elements, said corner brackets being provided with pintle openings extending along the end walls and at the top of said brackets, stacking bails provided with inturned pintles engaging the pintle openings of said corner brackets and swingable to erected position with the cross members thereof supported on the side reinforcing members, longitudinally disposed side and intermediate bottom bars disposed below and secured to the bottom and constituting slide rails, and sockets receiving the ends of the bottom bars and constituting wear members, said sockets being lapped upon the bottom of said cross pieces and having attaching flanges secured to said bottom and being provided with tongues engaged within the bottom cross pieces.

5. In a receptacle having bottom, side and end walls, reinforcing and stacking structure comprising corner uprights, bottom cross pieces secured to the lower ends of the corner uprights, side and end rim pieces secured on the outer sides of the side and end walls and to the upper ends of the corner uprights, downwardly facing U-shaped reinforcing members embracing intermediate portions of the side rim pieces and secured thereto, pivotally mounted stacking bails swingable to erected position with the cross members thereof supported on the side reinforcing members, longitudinally disposed side and intermediate bottom bars disposed below and secured to the bottom, and side and intermediate sockets being lapped upon the bottom of said cross pieces and receiving the ends of the bottom bars and having attaching flanges secured to the bottom and provided with tongues disposed within the bottom cross pieces, the side socket members being provided with angularly disposed outer flanges lapped upon and secured

to the side walls and having tongues engaged within the corner uprights, the outer socket members being of such length as to constitute stacking bail wear members.

5 6. In a receptacle having bottom, side and end walls, reinforcing and stacking structure comprising corner uprights, bottom cross pieces secured to the lower ends of the corner uprights, longitudinally disposed side and intermediate 10 bottom bars disposed below and secured to the bottom, and side and intermediate sockets being lapped upon the bottom of said cross pieces and receiving the ends of the bottom bars and having attaching flanges secured to the bottom and

15 provided with tongues disposed within the bottom cross pieces, the side socket members being provided with angularly disposed outer flanges lapped upon and secured to the side walls and having tongues engaged within the corner up- 20 rights.

7. A structure of the class described comprising corner uprights, bottom cross pieces secured to the lower ends of the corner uprights, side and end top rim pieces secured to the upper ends 25 of the corner uprights, downwardly facing U-shaped reinforcing members embracing intermediate portions of the side rim pieces and fixedly secured thereto, pivotally mounted stacking bails swingable to erected position with the 30 cross members thereof supported on the side reinforcing members, longitudinally disposed bottom bars lapped below said bottom cross pieces, and sockets receiving the ends of the bottom bars and provided with tongues engaged within the 35 bottom cross pieces and end flanges embracing the ends of said bottom bars.

8. A structure of the class described comprising corner uprights, bottom cross pieces secured to the lower ends of the corner uprights, side and end top rim pieces secured to the upper ends of the corner uprights, longitudinally disposed bottom bars lapped below said bottom cross pieces, and sockets receiving the ends of the bottom bars and provided with tongues engaged within the bottom cross pieces and end flanges embrac- 45 ing the ends of said bottom bars.

9. A structure of the class described comprising corner uprights, bottom cross pieces secured to the lower ends of the corner uprights, side and end top rim pieces secured to the upper ends of the corner uprights, longitudinally disposed bottom bars lapped below said bottom cross pieces, and sockets receiving the ends of the bottom bars and provided with tongues engaged within and welded to the bottom cross pieces.

55 10. A receptacle comprising inwardly facing angled corner uprights, inwardly facing angled bottom cross pieces secured to the lower ends of the corner uprights, side and end rim pieces secured to the upper ends of the corner uprights, pivotally mounted stacking bails swingable to erected position with the cross members thereof supported on the side rim members, longitudinally disposed bottom bars lapped below said bottom cross pieces, sockets receiving the ends of the bottom bars and having tongues engaged within the bottom cross pieces and end flanges embracing the ends of said bottom bars, and bottom side and end walls disposed with their 60 ends within the angles of said uprights and bottom cross pieces and supported thereby and by said rim pieces and said bottom bars.

70 11. A receptacle comprising corner uprights, bottom cross pieces secured to the lower ends of the corner uprights, a bottom and side and end

walls operatively associated with said corner uprights and bottom cross pieces, longitudinally disposed bottom bars lapped below said bottom cross pieces, and upwardly facing channel-shaped sockets having end flanges embracing the ends of said bottom bars, the ends of the bottom bars being disposed within the channel sockets and extending below the bottom cross pieces, said sockets having attaching flanges secured to the bottom and provided with tongues disposed above said bottom cross pieces, said tongues being welded to the upper sides of said cross pieces.

12. A receptacle comprising corner uprights, bottom cross pieces secured to the lower ends of the corner uprights, a bottom and side and end walls operatively associated with said corner uprights and bottom cross pieces, longitudinally disposed bottom bars lapped below said bottom cross pieces, and upwardly facing channel-shaped sockets having end flanges embracing the ends of said bottom bars, the ends of the bottom bars being disposed within the channel sockets and extending below the bottom cross pieces, said sockets having attaching flanges secured to the bottom and provided with tongues disposed above said bottom cross pieces.

13. A receptacle comprising a bottom, bottom end pieces disposed below the bottom, bottom supporting bars lapped below said bottom cross pieces, and sockets embracing the ends of the bottom bars and having attaching flanges secured to the bottom and provided with tongues disposed between said bottom cross pieces and bottom, said tongues being welded to the upper sides of said cross pieces, said bottom bars being secured to the bottom intermediate the said sockets.

14. A receptacle comprising a bottom, bottom end pieces disposed below the bottom, bottom supporting bars lapped below said bottom cross pieces, and sockets embracing the ends of the bottom bars and having attaching flanges secured to the bottom and provided with tongues disposed between said bottom cross pieces and bottom.

15. A receptacle comprising corner uprights, bottom cross pieces secured to the lower ends of the corner uprights, bottom supporting bars

lapped below said bottom cross pieces, and sockets receiving the bottom bars, said sockets having flanges provided with tongues lapped upon said bottom cross pieces and welded thereto and end flanges embracing the ends of said bottom bars.

16. A receptacle comprising corner uprights, bottom cross pieces secured to the lower ends of the corner uprights, bottom supporting bars lapped below said bottom cross pieces, and socket members receiving the ends of the bottom bars, said sockets having flanges provided with tongues lapped upon said bottom cross pieces and end flanges embracing the ends of said bottom bars.

17. A structure of the class described comprising corner uprights and bottom cross pieces secured to the lower ends of said uprights, a bottom, and side and end walls supportingly engaged with said corner uprights and bottom cross pieces, bottom bars disposed adjacent the edges of the bottom and lapped below said bottom cross pieces, and sockets lapped upon the bottom of said bottom cross piece and receiving the ends of the bottom bars and provided with inner flanges secured to the bottom and upturned outer flanges overlapping and secured to the side walls and end flanges embracing the ends of said bottom bars, the inner flanges being provided with tongues engaging the inner sides of the corner uprights.
